CATHODE-CONTROLLED WAVE GENERATORS

George W. Gray, Lambertville, N. J., assignor to Radio Corporation of America, a corporation of Delaware

Application December 29, 1950, Serial No. 203,317

The terminal 15 years of the term of the patent to be granted has been disclaimed

12 Claims. (Cl. 250—36)

This invention relates to electrical wave generators and has particular reference to that type of a generator of waves of complex form which is known as a multivibrator.

Multivibrators have been used extensively to produce waves of complex forms, particularly those known generally as square or rectangular waves. An ideal square wave has relatively steep leading and trailing edges and substantially flat tops or crests. Most multivibrators of the prior art produce waves which only approximate these characteristics. A multivibrator which produces a wave most closely approximating these characteristics is one known as a symmetrical cathode-coupled astable multivibrator. A typical example of such a device is disclosed in the book entitled "Wave Forms" published by McGraw-Hill Book Co., Inc., New York, New York, and appears in Figures 5-18 at page 173. In this multivibrator the resistive-capacitive cross-couplings between each of the tube anodes and the opposite control grids are of such long time constants that the oscillation frequency is not determined by them. Instead, this frequency is established by a capacitor coupled between the cathode circuits of the tubes. From the wave forms produced by this device shown in Figures 5-19 also at page 173 of this book, it may be seen that the developed wave has fairly steep leading and trailing edges. However, only the positive loops of the wave have substantially flat crests. The negative loops have decided slopes with the exponential curvature which is characteristic of prior art multivibrators.

Consequently, in order to utilize such a wave for many purposes, it is necessary to shape it additionally so as to produce relatively flat crests in both loops of the wave. Such an operation requires additional apparatus which adds to the cost of making the square wave generator, as well as to the cost of operating it.

Accordingly, it is an object of this invention to provide an improved multivibrator which is capable of generating substantially rectangular waves.

Another object of the invention is to provide an improved square wave generator by which the developed waves have substantially flat crests and in which a novel means of synchronizing from an external source is employed.

A further object of the invention is to provide an improved symmetrical cathode-coupled astable multivibrator having anode and cathode circuits suitably related to produce square waves having relatively flat crests in both halves of the wave.

In accordance with this invention, a multivibrator is provided which consists essentially of means, such as two electron tubes defining two space discharge paths, each of which includes at least an anode, a cathode, and a control grid. Cross-couplings are provided from each anode circuit to the opposite control grid in a conventional manner for multivibrators. The time constants of these couplings, however, are long compared with the

2

period of oscillation of the device. Respective circuits including impedance devices are coupled to the cathodes of the space discharge paths. The cathode-connected impedances are at least as large as, and preferably considerably larger than, the anode circuit impedances, in accordance with this invention. The timing of the multivibrator is determined by a capacitor coupled symmetrically between the two cathode circuits.

In one particular embodiment of the invention the cathode-connected circuits include devices which are effectively constant current devices, such as electron tubes of the pentode type. In this form of the invention, control signals may be impressed upon one of the pentodes for the synchronous operation of the multivibrator.

The novel features that are considered characteristic of this invention are set forth with particularity in the appended claims. The invention itself, however, both as to its organization and method of operation, as well as additional objects and advantages thereof, will best be understood from the following description when read in connection with the accompanying drawing.

In the drawing:

Figure 1 is a circuit diagram of the basic circuits of a multivibrator illustratively embodying this invention;

Figure 2 is a series of curves representing wave forms produced by apparatus embodying the invention and referred to in describing the operation of the apparatus; and,

Figure 3 is a circuit diagram of another form of the invention employing pentode electron tubes as parts of the cathode-connected impedances of a multivibrator in accordance with this invention.

Reference first will be made to Figure 1 of the drawing. The multivibrator embodying this invention, as shown here, includes two electron tubes 11 and 12. It will be understood that these tubes may be in separate envelopes as shown. Alternatively, they may be enclosed within the single envelope of a dual triode, for example. In any case, there are defined two space discharge paths, each of which includes an anode, a cathode and a control grid. Space current for the tubes 11 and 12 is derived from a source indicated at +B through resistors 13 and 14 coupled respectively to the anodes of these tubes. The anode of tube 11 is cross-coupled to the control grid of tube 12 by a circuit including a capacitor 15 and a resistor 16. Similarly, the anode of the tube 12 is cross-coupled to the control grid of tube 11 by a circuit which includes a capacitor 17 and a resistor 18. In each case, the resistors are connected to the respective cathodes of the tubes. Also, in each case, the cross-coupling has a long time constant as compared to the period of oscillation of the multivibrator. Consequently, the oscillation frequency of the multivibrator is not determined by these cross-couplings.

The cathodes of the tubes 11 and 12 are symmetrically coupled by a timing capacitor 19. Also, the cathodes of the tubes 11 and 12 are connected to ground through resistors 21 and 22 respectively. In accordance with a feature of the present invention, the impedance of the resistors 21 and 22 is at least equal to, and preferably greater than, the impedance of the anode-connected resistors 13 and 14. Typical magnitudes for the resistors 21, 22 might be thirty times greater than the magnitudes of the anode-connected resistors 13, 14.

The operation of the multivibrator shown in Figure 1 is somewhat similar to that of the multivibrator disclosed in the publication referred to. The anode-to-grid cross-couplings and the cathode coupling between the tubes provide two paths for regenerative action. The cross-couplings provide a regenerative action which is insufficient in itself to cause oscillation because of the fact

that the cathode-connected resistor 21 is made larger than the anode-connected resistor 13. Accordingly, the apparatus will not oscillate at all without the cathode-coupling capacitor 19. The reason for this is that, the gain produced from the grid circuit to the anode circuit of each tube is less than unity. Therefore, the gain of the entire loop, which includes both of the cross-couplings between anodes and control grids is less than unity. Consequently, no oscillations will occur even though the phase of the feed-back energy through the cross-couplings between the tubes is of regenerative character.

The inclusion of the cathode coupling capacitor 19 in the circuit, however, provides another regenerative feed-back loop which is effective to make the apparatus oscillate. The way in which the circuit, including the coupling capacitor 19, operates to produce this result, may be explained in the following manner. Assume that the tube 11 is conducting and that the tube 12 is non-conducting. A portion of the space current, which is conducted by the tube 11, traverses a circuit including the capacitor 19 and the resistor 22. As the capacitor 19 becomes charged, this current flow decreases in magnitude thereby causing the potential of the cathode of tube 12 to decrease toward ground potential. This potential change tends to render the tube 12 conductive. The rate at which this cathode potential changes depends upon the time constant of the circuit and is determined principally by the capacitor 19 and the resistor 22.

Another portion of the space current in the tube 11 traverses the cathode-connected resistor 21. This portion of the current, however, does not vary substantially. The resultant decrease in the total space current through tube 11 causes a slight increase in a positive sense of the anode potential of the tube 11. By means of the cross-coupling, including the capacitor 15 and the grid resistor 16, this increased potential is impressed upon the control grid of the tube 12. This potential change also tends to render the tube 12 conductive.

It is seen, therefore, that the described potential changes of the control grid and cathode of the tube 12 both are of the character necessary to render this tube conducting. The regenerative feed-back loop, including the coupling capacitor 19, provides more than enough gain to produce oscillation. The grid-to-anode loop adds to the regeneration and thereby accelerates the described operation of the device, even though by itself it is insufficient to cause oscillation. As soon as space current begins to flow in the tube 12, it increases to a maximum substantially instantaneously and space conduction in the tube 11 is terminated substantially instantaneously in the characteristic manner of multivibrators. The described cycle of operation is repeated during the next succeeding interval of time substantially in the manner described except that the current flow through the coupling capacitor 19 is in a direction opposite to that described. This current then traverses the cathode-connected resistor 21, as well as the space discharge path of the tube 12.

As described, the operation of the present multivibrator is somewhat similar to that of the multivibrator disclosed in the publication referred to. There is one very important difference, however. This is produced by the described relationship between the anode- and cathode-connected resistors 13, 14 and 21, 22 respectively. The materially improved results obtained by the present devices are graphically illustrated in Figure 2 to which reference now will be made. The curve 23 represents the typical output wave which is derived from the anode, for example, of one of the multivibrator tubes of a device such as that shown in the publication referred to. The leading and trailing edges, such as 24 and 25 respectively, of the pulses are not as steep as frequently desired.

Aside from the fact that the wave 23 of the prior art apparatus does not have leading and trailing edges as steep as might be desired, it is seen that, in one half of the cycle, the wave has a substantially exponentially

sloping crest 26. The sloping crest 26 is produced principally because of the substantially exponential decrease of the charging current through the cathode coupling capacitor, corresponding to the capacitor 19 of the present apparatus. As a consequence, in order to utilize a wave such as 23, it is necessary to provide apparatus for clipping off the portion of the wave including the sloping crest 26.

The multivibrator, in accordance with the present invention, however, by virtue principally of the employment of anode- and cathode-coupled resistors in the described relationship produces a wave such as 27 in the anode circuit of either of the tubes 11 and 12. It is seen that this wave has very steep leading and trailing edges 28 and 29. It also has a lower, or negative polarity, crest 31 which is substantially flat. Actually, the illustration in Figure 2 is quite exaggerated. It has been found to be well within the capabilities of apparatus in accordance with this invention to generate a square wave in which the slope of the crest 31 is less than 5% of the total amplitude of the wave. By this is meant that the difference in amplitude between the leading and trailing edges 28 and 29 of the wave 27 is less than 5% of the amplitude of the wave as measured at the trailing edge 29, for example.

The slopes of the crests 26 and 31 of the waves 23 and 27, respectively, are produced as a result of a variation in the current through the coupling capacitor such as 19 of the apparatus of Figure 1. As described previously, this current flows through the conducting tube, such as 11, and also through the cathode-connected resistor, such as 22, associated with the non-conducting tube, such as 12. As is well-known, the potential at the point in this circuit to which the cathode of the non-conducting tube, such as 12, is connected varies, in a negative sense, toward ground potential as the coupling capacitor 19 changes from a charged condition of one polarity to a charged condition of the other polarity.

Consequently, as a result of this potential change, the current through the capacitor 19 and also through the conducting tube such as 11 decreases. A decrease in the current through the tube 11 causes the potential at the anode of this tube to increase in a positive sense. The potential at the cathode of the tube 11 at the same time tends to change in a negative sense toward ground potential. The later effect, however, in most cases, is negligible because it is such a small percentage of the potential variation at the anode of the tube.

In multivibrators of this general type used previously, the cathode-connected resistors have been of relatively low impedance with respect to the anode-connected resistors. Consequently, the total voltages developed at the cathodes of the tubes, such as 11 and 12 relative to ground, have been relatively small. The absolute magnitude of the voltage changes occurring at the cathode of either of the tubes as a result of the charging and discharging of the coupling capacitor such as 19 are approximately the same as in the present invention. In the prior art multivibrators these voltage changes have been of such magnitudes that they represent relatively large percentages of the total voltages developed across the cathode-connected resistors.

In the present case, however, the total voltage developed across the high impedance cathode-connected resistors is very much greater than is possible with the same tube currents in the prior art arrangements. Accordingly, the voltage changes occurring at the cathodes of the tubes as a result of the charging and discharging of the capacitor 19 are a relatively small percentage of the total voltages.

It is seen, therefore, that in the present arrangement, the voltage variations occurring at the cathodes of the tubes 11 and 12 are produced by operating on the extreme upper portion of the exponential curve, which is characteristic of the operation of a circuit having capacitance and resistance. This portion of the curve is sub-

stantially linear. In multivibrators of the prior art where the voltage variations of the cathodes of the tubes represents a relatively large percentage of the total voltage developed, operation occurs over a substantial portion of the characteristic curve and, consequently, includes a considerable portion which is non-linear. These voltage variations produce the slopes in the negative loops of the waves developed at the anodes of the multivibrator tubes as previously described.

The wave 32 of Figure 2 represents the voltage at the cathode of either of the tubes 11 and 12. It is seen that, while the tube is in a conducting state, the cathode potential is maintained substantially constant as indicated by the portion 33. As soon as a conducting tube is rendered non-conducting, the cathode voltage substantially instantaneously increases in a positive sense to a point such as 34. As a result of the described change in the charging of the coupling capacitor 19, the voltage at the cathode of the non-conducting tube decreases substantially linearly toward ground until a point such as 35 is reached at which time the switching action between the tubes is initiated.

It will be appreciated that the switching action between the two tubes 11 and 12 occurs very rapidly because of two principal facts. One is that no grid current is drawn by virtue of the described character of the cross-couplings between the anodes and control grids of the tubes. The other is that there are provided two positive feed-back loops both acting in a regenerative capacity. Immediately after the switch has been made from one tube to another, the tube which is rendered nonconducting is, in a sense, doubly cut off. Its control grid is driven negative by means of the coupling to the anode of the conducting tube. Also, its cathode is rendered positive by means of the coupling capacitor 19 which impresses upon it the positive impulses produced at the cathode of the conducting tube at the time of its being rendered conducting. This cathode potential is represented at the point 34 of the curve 32 of Figure 2.

The slope such as 31 of the wave 27 shown in Figure 2 may be minimized by making the cathode-connected resistors 21 and 22 as large as possible compared to the cathode impedance of either of the tubes when it is conducting. The cathode impedance of a conducting tube may be represented by the expression

$$\frac{1}{g_m} + \frac{R_L}{\mu}$$

where g_m is the transconductance; μ is the amplification factor and R_L is the anode impedance of the tube. If the cathode-connected resistor is made too large, the transconductance of the tube becomes excessively low because the space current of the tube is reduced too much and the ratio between the cathode-connected resistor of the non-conducting tube and the cathode impedance of the conducting tube is reduced. An optimum cathode-connected resistor value produces a minimum slope of the negative loops of the generated wave.

As indicated previously, the frequency of the cathode-controlled multivibrator in accordance with this invention is a function of the value of the coupling capacitor 19. It has been found that the frequency at which this multivibrator is capable of operating covers a relatively large range. Furthermore, the frequency variation is substantially linear with values of the coupling capacitor over most of the range. For example, in a particular case, it was found that the frequency of oscillation of the multivibrator could be varied linearly from a frequency in excess of one megacycle down to a frequency which corresponds generally with the time constant of the anode-to-grid cross-coupling circuits. In one case, the capacitors 15 and 17 were .005 microfarad and the grid resistors 16 and 18 were 10 megohms. The time constant of the cross-coupling circuits, therefore, is substantially $\frac{1}{20}$ of a second. As a consequence, it was found that

the oscillation frequency of the multivibrator began to depart from a linear curve at about 60 cycles per second.

It also has been found that the range of the linear relationship between the oscillation frequency and the value of the coupling capacitor 19 may be extended by increasing substantially the value of the grid resistors 16 and 18. In a particular case, these resistors were entirely removed. Leakage currents in the remaining circuits were found to be sufficient to enable the apparatus to operate substantially in the manner described. The essential difference, however, is that the time constant of the cross-coupling circuits between the anodes and control grids of the tubes 11 and 12 is much longer. As a consequence, the linearity of the frequency curve may be extended into the frequency region of substantially one cycle per second.

In view of the foregoing description of the mode of operation of the multivibrator apparatus of Figure 1 whereby it has been demonstrated that the negative loops of the generated wave may have minimum slopes, it is seen that what is ideally required as cathode-connected resistors such as 21 and 22 of Figure 1 are devices having maximum impedances and also the facility of conducting appreciable current. Also, it should be clear from the foregoing description that, in order to substantially eliminate all slope from the crests of the negative loops of the developed wave, it is necessary that the current flowing through the coupling capacitor and the associated resistive circuits be maintained substantially constant. In accordance with another feature of this invention, this is accomplished by employing electronic devices having a substantially constant current conducting capability as part, at least, of the cathode-connected resistors.

Accordingly, reference now will be made to Figure 3 of the drawing showing another embodiment of the invention in which substantially all slope of the crests of the developed wave is eliminated and also one which is susceptible of synchronous control from an external source. In this form of the invention, pentode electron tubes 36 and 37 are connected from the cathodes of tubes 11 and 12, respectively, and through a common variable resistor 38 to ground. The suppressor grids of the pentodes 36 and 37 are connected to their associated cathodes in a conventional manner. Also, the screen grids of these tubes are connected to one another by a differential voltage dividing resistor 39. Positive voltage is impressed through a resistor 40 upon a variable tapping point on the resistor 39 so as to differentially vary the current capabilities of the tubes 36 and 37. The screen grids of the pentodes 36 and 37 also are conventionally bypassed to ground by capacitors 41. The control grid of the tube 36 is directly connected to ground as shown. The control grid of the tube 37 is coupled by a capacitor 42 and a resistor 43 to the synchronizing signal input terminals 44.

The anode-connected resistors for the multivibrator tubes 11 and 12 are effectively the same as in the embodiment of the invention shown in Figure 1. The resistor 14 associated with the tube 12, however, is indicated as comprising two serially-connected resistor elements 14a and 14b. It will be understood that these two elements together may have substantially the same value as the resistor 13 associated with the tube 11. The junction point between the resistor elements 14a and 14b is connected to one of a pair of output terminals 45.

The multivibrator, in accordance with this form of the invention, operates substantially in the same manner as that shown in Figure 1. In this case, however, the resistance connected to the cathode of the multivibrator tubes 11 and 12 consists essentially of the respective anode-cathode impedances of the pentodes 36 and 37. The impedances of these tubes is affected by the adjustment of the variable contact on the resistor 39. For any given value of impedance, however, the tubes 36 and 37 are essentially constant current devices. Consequently,

as the potential of the cathodes of the non-conducting ones of the multivibrator tubes 11 and 12 varies with the change of the charging of the coupling capacitor 19, the current conducting capabilities of the associated pentodes do not change. Therefore, the current traversing the conducting one of the multivibrator tubes 11 and 12 does not vary. Hence, there is no voltage change produced at either the cathode or anode of the conducting tube which would produce a slope in the crest of the negative half cycles of the wave developed for impression upon the output terminals 45.

A variation of the resistor 38 provides a fine frequency control of the multivibrator. This control is affected because the value of the resistor determines in some measure the magnitude of the current drawn by the pentode tubes 36 and 37. Accordingly, the time constants of the frequency determining circuits which include the capacitor 19 may be varied sufficiently to produce relatively small changes of the operating frequency.

As in the case of most multivibrators, the one in accordance with the present invention is susceptible of external control whereby it may be made to operate synchronously with other apparatus. In this case, the synchronizing pulses are impressed upon the control grid of the pentode tube 37 as described. A control of one of the pentode tubes by such means operates as a switch by which the multivibrator may be started and stopped. Accordingly, even though it is of the astable type whereby it will operate in a free running manner exclusive of any external control, it may be synchronously operated in a manner such as that described.

It will be appreciated that a multivibrator in accordance with the present invention is not necessarily limited for use in generating so called square waves in which the positive and negative half cycles are of substantially equal time durations. It is considered to be within the scope of the invention to operate the device in such a manner that other rectangular wave forms may be developed in which the time durations of the positive and negative half cycles are not of the same time durations. Such operation in accordance with well-known multivibrator practice requires that one of the electron tubes be maintained in a conducting state longer than the other tube. Ordinarily, such type of operation may be achieved by unbalancing the two halves of the multivibrator, particularly the frequency determining circuits coupling the two tubes. This type of operation may be achieved in the present case by substantially similar means. For example, the cathode-connected resistors, such as 21 and 22 of Figure 1, may be of different values. The time constants of the two frequency determining circuits both of which include the coupling capacitor 19 accordingly may be made sufficiently different to cause one of the tubes to be conducting for longer times than the other tube. In the form of the invention shown in Figure 3, the unbalance is produced by positioning the movable contact of the voltage dividing resistor 39 so that a higher positive potential is impressed upon the screen grid of one of the pentodes than that of the other pentode.

It may be seen from the foregoing description of the illustrative embodiments of the invention disclosed herein that the proper relationship between the cathode anode connected resistors enables the operation of a multivibrator in such a way as to develop good square or rectangular waves having steep leading and trailing edges and substantially no sloping crests in any part of the cycle. Accordingly, the output wave may be employed directly without the necessity of employing clipping or other wave shaping apparatus.

Also, in accordance with the foregoing description, it will be appreciated that the multivibrator in accordance with this invention is susceptible of operating over a relatively wide range of oscillation frequencies. Furthermore, such a device is of a character that a substantial linearity exists between the oscillation frequency and the

value of the coupling capacitor such as 19 throughout the entire operating frequency range. Moreover, as previously indicated, the device is readily susceptible of external control of synchronous operation.

5 What is claimed is:

1. A multivibrator comprising, means defining two space discharge paths, each of which includes an anode, cathode and a control grid, external circuits coupled respectively to said anodes and cathodes, cross-couplings between said space discharge paths, each of said cross-couplings including a capacitor connected between one of said anode circuits and the opposite control grid, said capacitors having values such that said cross-couplings have relatively long time constants compared to the period of oscillation of said multivibrator, a resistor connected between said control grid and said cathode of each of said space discharge paths, whereby said cross-couplings do not determine the oscillation frequency of said multivibrator and the regenerative action provided by said cross-couplings is insufficient in itself to cause oscillations to be produced by said multivibrator, impedance devices connected respectively in said cathode circuits for traversal by currents flowing in said space discharge paths, the impedance of said devices being at least as great as the impedances of said anode circuits, and a capacitor connected between said cathode circuits for effecting alternate operation of said space discharge paths in a manner to develop a rectangular wave having substantially flat crests, whereby the difference in amplitude of the leading and trailing edges of the developed rectangular wave of said multivibrator is less than 5% of the amplitude of said wave as measured at the trailing edge of said wave.

2. A multivibrator comprising, means defining two space discharge paths, each of which includes at least an anode, a cathode and a control grid, respective cross-couplings between each of said anodes and the opposite control grids, each of said grids being connected to its respective cathode, said couplings having relatively long time constants compared to the period of oscillation of said multivibrator, whereby said cross-couplings do not determine the oscillation frequency of said multivibrator and the regenerative action provided by said cross-couplings is insufficient in itself to cause oscillations to be produced by said multivibrator, external circuits coupled respectively to said anodes and cathodes, impedance devices connected respectively to said cathodes for traversal by currents flowing in said space discharge paths, the impedances of said devices being materially greater than the impedances of said anode circuits, and a capacitor connected between said cathode circuits for effecting alternate operation of said space discharge paths in a manner to develop at one of said anodes a square wave having substantially flat crests, whereby the difference in amplitude of the leading and trailing edges of the developed rectangular wave of said multivibrator is less than 5% of the amplitude of said wave as measured at the trailing edges of said wave.

3. A multivibrator comprising, means defining two space discharge paths, each of which includes an anode, a cathode and a control grid, external circuits coupled respectively to said anodes and cathodes, cross-couplings between said space discharge paths, each of said cross-couplings including a capacitor connected between one of said anode circuits and the opposite control grid, said capacitors having values such that said cross-couplings have relatively long time constants compared to the period of oscillation of said multivibrator, impedance devices, each including a pentode electron tube connected respectively in said cathode circuits for traversal by currents flowing in said space discharge paths, the impedances of said devices being greater than the impedance of said anode circuits, and a timing capacitor connected between said pentodes for effecting alternate operation of said space discharge paths and also of said pentodes in such

a manner that the current flowing in either of said space discharge paths also traverses the pentode tube coupled to the cathode of the opposite space discharge paths, whereby to develop at one of said anodes a rectangular wave having substantially flat crests.

4. A multivibrator as defined by claim 3, and including additionally means for varying the current conducting capability of at least one of said pentode electron tubes whereby to control the respective time durations of the positive and negative half cycles of the developed rectangular wave.

5. A multivibrator as defined by claim 3, and including additionally means including the screen grids of said pentode electron tubes for differentially varying the current conducting capabilities of said pentode tubes whereby to control the respective time durations of the positive and negative half cycles of said developed wave.

6. A multivibrator as defined by claim 3 wherein, the screen grids of said pentode electron tubes have positive potentials impressed thereon, and including additionally means for differentially varying the positive potentials impressed upon said screen grids for effecting a control of the wave form developed by the multivibrator.

7. A multivibrator as defined by claim 3, and including additionally means for similarly varying the current conducting capabilities of both of said pentode electron tubes whereby to effect a variation of the oscillation frequency of the multivibrator.

8. A multivibrator as defined by claim 3, and including additionally a resistor connected in series with both of said pentode electron tubes, said resistor being variable whereby to effect a variation of the oscillation frequency of the multivibrator.

9. A multivibrator as defined by claim 3, and including additionally means for impressing synchronizing signals upon the control grid of one of said pentode electron tubes.

10. A multivibrator as defined by claim 3 wherein, said cross-couplings between the two space discharge paths include only capacitors.

11. A multivibrator comprising, a pair of triode electron tubes, each including an anode, a cathode and a control grid, capacitors respectively cross-connected between each of said anodes and the opposite control grids thereby providing cross-couplings having relatively long time constants compared with the period of oscillation of said multivibrator, resistors connecting said triode anodes to a source of space current, one of said resistors being provided with an intermediate terminal constituting an output terminal of said multivibrator, a pair of pentode electron tubes, each having an anode, a cathode, a control grid, a screen grid, and a suppressor grid and constituting constant current impedance devices, the anodes of said pentode tubes being connected respectively to the

cathodes of said triode tubes, a frequency-determining capacitor connected between the cathodes of said triode tubes, a single resistor connected in common between the cathodes of said pentode tubes and a point of relatively fixed potential, means including a variable resistor connected between a point of positive potential and the screen grids of said pentode tubes for varying the oscillation frequency of said multivibrator, means connecting the control grid of one of said pentode tubes to a point of relatively fixed potential, and means coupling the control grid of the other of said pentode tubes to a source of synchronizing signals.

12. A multivibrator circuit arrangement including a pair of triode tubes each having a cathode, a grid and an anode, impedance devices individually connected to the anode circuits of said tubes, capacitors cross-coupling the anode of each of said tubes to the grid of the other tube to form an astable multivibrator circuit, at least one impedance device including at least one electron discharge device having cathode, control, grid and anode electrodes connected in the cathode circuit of one of said tubes with the anode electrode connected to the cathode of said one tube, another device connecting the cathode of the other tube to a point of fixed reference potential and having a value of impedance at least as great as that of the impedance device connected to the anode of said other tube, means connecting the cathode and grid electrodes of said electron discharge device to a point of fixed reference potential, and means to impress a signal between the control and cathode electrodes of said electron discharge device to control operation of said astable multivibrator circuit.
